UNITED STATES PATENT OFFICE.

HERMAN C. PRIEBE, OF BLUE ISLAND, ILLINOIS.

DRAFT-GEAR.

1,282,941.

Specification of Letters Patent. Patented Oct. 29, 1918.

Application filed July 22, 1918. Serial No. 246,129.

To all whom it may concern:

Be it known that I, HERMAN C. PRIEBE, citizen of the United States, residing at Blue Island, in the county of Cook and State of Illinois, have invented a certain new and useful Improvement in Draft-Gears, of which the following is a full, clear, concise, and exact description.

My invention relates to draft gears of the type employing inner and outer followers actuated by couplers, rockers individual to the followers, and movable thereby, and means, operating through said rockers, for resisting the approach of the followers toward each other. This motion resisting means is preferably in the form of spring mechanism, particularly where friction is not relied upon to resist the relative movement of the followers.

It is the object of my invention to improve the construction and arrangement of the component parts of the gear which have been named whereby the desired effectiveness in operation may be secured with the most simple construction of gear.

In practising my invention I employ at least two or more sets of rockers, each set having one rocker individual to each follower and movable thereby. The two rockers of each set interact preferably by providing them with opposed engaging curved faces and are interposed between the motion resisting means which is subdivided into two elements, each element being individual to a follower and in alignment with the other element and with both followers. Interacting rockers are assembled with a floating retaining block or member common thereto that prevents the rockers from falling out, which may happen in the event of breakage or distortion of the center sills and other parts of the under structure of the car.

I will explain my invention more fully by reference to the accompanying drawings showing the preferred embodiment thereof and in which Figure 1 is a sectional view taken generally on line 1—1 of Fig. 2; Fig. 2 is a sectional view taken generally on line 2—2 of Fig. 1; Fig. 3 is a sectional view on line 3—3 of Fig. 1; Fig. 4 is a sectional view on line 4—4 of Fig. 1; Fig. 5 is a view illustrating some of the elements appearing in Fig. 1 but in changed positions; Fig. 6 is a perspective view illustrating a follower and

two rockers belonging to different sets and each individual to said follower; and Fig. 7 is a perspective view illustrating a floating block between the sets of followers.

Like parts are indicated by similar characters of reference throughout the different figures.

The coupler 1 has a coupler shank 2 to which the outer ends of a yoke 3 are secured by means of rivets or bolts 4. An outer follower 5 is engaged by the coupler butt 6 and is moved inwardly whenever the coupler is subject to sufficient pushing strain. The inner follower 7 is engaged by the inner end of the coupler yoke 3 and is movable outwardly when the coupler is subject to sufficient pulling strain. The extent to which the outer follower is movable outwardly is limited by the outer stops 8. The extent to which the inner follower 7 is movable inwardly is limited by the inner stops 9. All of said stops are riveted against the center sills 10 that form a part of the underframe structure of a car equipped with the draft gear. The followers 5 and 7 are in the nature of spring barrels which house the co-operating spring elements 11 and 12 of mechanism that is employed to resist the movement of either follower toward the other and to effect the return of the followers toward the stops respectively pertaining thereto.

One or more sets of rockers are disposed between the followers. I have illustrated two sets of rockers, each set including a rocker 13 individual to the outer follower 5 and a rocker 14 individual to the inner follower 7.

The outer follower 5 carries two seats or mountings 5¹, one for each rocker 13 to rock upon. The inner follower 7, similarly, carries two seats or mountings 7¹, one for each rocker 14 to rock upon. All of the rockers are of similar construction, the rockers of each set being symmetrically arranged.

They interact preferably by being pressed in direct engagement by the coiled springs 11, 12 of the motion resisting mechanism, these springs serving to oppose the relative movement of the followers by opposing the attendant follower effected rocking movement of the rockers. The rockers of each set, where in engagement, are formed with curved engaging faces whereby each rocker of a set causes the other rocker of the same set to turn upon its seat or mounting.

Each rocker has a part thereof which is in engagement with the seat provided upon the follower individual thereto curved to form a segment of a cylinder, the seat upon the follower 5 lower engaged thereby being similarly curved. By this construction each rocker has an axis of rotation which is substantially fixed with respect to the follower individual thereto. The aforesaid seats 5¹, 7¹ and the rockers engaging the same are desirably placed upright, in which event the follower 5 is provided with inner ledges 5² between which the rockers 13 are disposed and the follower 7 is provided with outer ledges 7² between which the rockers 14 are disposed, these ledges preventing the rockers from moving up and down materially. Each of the opposed engaging curved faces of the rockers of each set has its distance from the axis of the rocker increased as such curvature approaches the axis of the springs or gear. This formation of the curvature permits the approach of either follower toward the other when the gear is subject to sufficient pushing or pulling strain. By the arrangement illustrated each spring acts upon both rockers of a set and the rockers form a motion resisting means between the springs, all of these elements thus being interacting when either follower is in motion. Moreover, the entire structure is very compact, being embraced between the sides of the yoke and the center sills. A floating block or member 16 is interposed between and inclosed by the rockers of each set. This block is preferably hollow and has two projections 17 that extend longitudinally from the inner and outer ends of the blocks and horizontally of the gear 40 into the bores of the aligned springs the springs as well as the rockers being thus maintained in assembly with each other and with the followers in the event of the breakage or distortion of the center sill or other parts of the under structure. In order that said block may thus be inclosed by the rockers said rockers are provided with recesses 18 in their opposing faces between their top and bottom walls 19 which have the opposed engaging curved faces of the rockers. These recesses 18 are of such size as jointly to form a substantially closed space adapted to retain the floating member in all positions of the rockers without necessitating separation of their engaged curved faces. In order that the floating member may not be loose the inner and outer upright walls thereof are constantly engaged by the curved faces 20 of the rockers. While I have herein shown and particularly described the preferred embodiment of my invention I do not wish to be limited to the precise details of construction shown as changes may readily be made without departing from the spirit of my invention, but

having thus described my invention, I claim as new and desire to secure by Letters Patent the following:

1. A draft gear including a coupler; inner and outer followers actuated thereby and movable each toward the other; springs, one individual to each follower, for resisting the approach of the followers toward each other; two interacting rockers, one rocker being individual to each follower and actuatable thereby, said rockers being interposed between and engaged by said springs; and a floating member in assembly maintaining relation to said rockers.

2. A draft gear including a coupler; inner and outer followers actuated thereby and movable each toward the other; motion resisting elements, one individual to each follower, for resisting the approach of the followers toward each other; two interacting rockers, one rocker being individual to each follower and actuatable thereby, said rockers being interposed between and engaged by said motion resisting elements; and a floating member in assembly maintaining relation to said rockers.

3. A draft gear including a coupler; inner and outer followers actuated thereby and movable each toward the other; springs, one individual to each follower, for resisting the approach of the followers toward each other; two interacting rockers, one rocker being fulcrumed upon each follower and actuatable thereby, said rockers being interposed between and engaged by said springs; and a floating member in assembly maintaining relation to said rockers.

4. A draft gear including a coupler; inner and outer followers actuated thereby and movable each toward the other; motion resisting elements, one individual to each follower, for resisting the approach of the followers toward each other; two interacting rockers, one rocker being fulcrumed upon each follower and actuatable thereby, said rockers being interposed between and engaged by said motion resisting elements; and a floating member in assembly maintaining relation to said rockers.

5. A draft gear including a coupler; inner and outer followers actuated thereby and movable each toward the other; springs, one individual to each follower, for resisting the approach of the followers toward each other; two interacting rockers, one rocker being individual to each follower and actuatable thereby, said rockers being interposed between and engaged by said springs; and a floating member between and inclosed by said rockers.

6. A draft gear including a coupler; inner and outer followers actuated thereby and movable each toward the other; motion resisting elements, one individual to each follower, for resisting the approach of the fol-

lowers toward each other; two interacting rockers, one rocker being individual to each follower and actuatable thereby, said rockers being interposed between and engaged by said motion resisting elements; and a floating member between and inclosed by said rockers.

7. A draft gear including a coupler; inner and outer followers actuated thereby and movable each toward the other; springs, one individual to each follower, for resisting the approach of the followers toward each other; two interacting rockers, one rocker being fulcrumed upon each follower and actuatable thereby, said rockers being interposed between and engaged by said springs; and a floating member between and inclosed by said rockers.

8. A draft gear including a coupler; inner and outer followers actuated thereby and movable each toward the other; motion resisting elements, one individual to each follower, for resisting the approach of the followers toward each other; two interacting rockers, one rocker being fulcrumed upon each follower and actuatable thereby, said rockers being interposed between and engaged by said motion resisting elements; and a floating member between and inclosed by said rockers.

9. A draft gear including a coupler; inner and outer followers actuated thereby and movable each toward the other; springs, one individual to each follower, for resisting the approach of the followers toward each other; two interacting rockers, one rocker being fulcrumed upon each follower and actuatable thereby, said rockers being interposed between and engaged by said springs; and a floating member between and inclosed by said rockers, said member having projections extending into the bores of said springs.

10. A draft gear including a coupler; inner and outer followers actuated thereby and movable each toward the other; springs, one individual to each follower, for resisting the approach of the followers toward each other; two interacting rockers, one rocker being individual to each follower and actuatable thereby, said rockers being interposed between and engaged by said springs; and a floating member between and inclosed by said rockers, said member having projections extending into the bores of said springs.

In witness whereof, I hereunto subscribe my name this eighteenth day of July, A. D. 1918.

HERMAN C. PRIEBE.
